Fig. 2

To all whom it may concern:

Be it known that I, Hans J. Kaufman, a citizen of the United States, residing at Cuba, in the county of Allegany and State of New York, have invented a new, original, and ornamental Design for a Chair, of which the following is a specification, reference being had to the accompanying drawing, forming part thereof, and in which

Fig. 1 is a perspective view of a chair, showing my new design, being taken generally from the front; and

Fig. 2 is a perspective view thereof, being taken generally from the rear.

I claim:

The ornamental design for a chair, substantially as shown.
